Application filed June 13, 1891. Serial No. 396,195. Term of patent 7 years.

To all whom it may concern:

Be it known that I, FREELAND W. OSTROM, a citizen of the United States, residing at Bridgeport, in the county of Fairfield and State of Connecticut, have invented and produced a new and original Design for a Soap-Stand; and I do hereby declare the following to be a full, clear, and exact description of the invention, such as will enable others skilled in the art to which it appertains to make and use the same.

The accompanying drawing is a perspective of a soap-stand, showing my design.

The leading feature of my design consists in the broadly-diminished scalloped arms rising in continuity from the base and describing a general curve, as shown.

I claim—

In testimony whereof I affix my signature in presence of two witnesses.
